TREATING CORROSIVE OILS

Charles A. Cohen, Elizabeth, N. J., assignor to
Standard Oil Development Company, a corpora-
tion of Delaware

No Drawing. Application December 29, 1939,
Serial No. 311,592

10 Claims. (Cl. 196—41)

This invention relates to an improved process for refining hydrocarbon oils. More particularly, it is concerned with the treatment of oils of the white oil type such as medicinal oils, transformer oil, insecticide base oils, refrigerator oils, or cosmetic oils and lubricating oils like spindle oil or motor oil which have during the process of their refinement been subjected to the action of fuming sulfuric acid.

Highly acid treated oils or white oils are prepared by the drastic treatment of a hydrocarbon oil having a viscosity in the range of 30-1000 seconds Saybolt at 100° F. with fuming sulfuric acid, followed by separating the acid sludge from the oil, neutralizing the acid oil with an alkali, removing the alkali sulfonates from the oil by dilute alcohol or other solvents and steaming the oil to remove the solvent and other volatile constituents. The oil at this stage is known as a neutral oil and varies in color from -10 to +20 Saybolt. It is then finished by percolating it thru a bed of absorbent clay to give a finished white oil of +30 Saybolt in color.

Many such oils are, however, corrosive in character and will cause the corrosion of copper in less than two hours when subjected to the copper strip test. This test consists in polishing a strip of copper measuring $\frac{1}{2}$ to 3" with tripoli or other fine abrasive, immersing the copper strip in a sample of the oil to be tested and heating for from 2 to 3 hours in a steam bath at a temperature of 212° F. The results are rated numerically as follows: No. 1 shows no change in appearance of the original copper strip; No. 2 shows a slightly discernable yellow color but is still passable; No. 3 which fails, shows a pronounced bronze coloration; No. 4 shows a deep bronze color and No. 5 is blue-black. Ordinarily, oils which have failed to pass the copper strip test have had to be recycled thru the acid treatment in an attempt to make them less corrosive. At times it has been necessary to recycle the corrosive oils thru the acid treat three or four times before an acceptable copper strip test is obtained upon them.

Some success has been had in treating finished white oils to improve their copper strip test by the use of calcium or magnesium hydroxide. However, this method is not applicable to medicinal white oils because oils treated with these reagents acquire an objectionable taste. Also, the quantity of calcium and magnesium hydroxide used is bulky and its removal necessitates additional handling of the finished oil which increases the possibility for contamination. In addition, there are times when in order to obtain good

copper strip tests by the calcium and magnesium hydroxide, it has been necessary to give the oil several treatments with these hydroxides.

Alcoholic potassium hydroxide has also been used for the elimination of corrosiveness from acid-treated oils and in the proportion of one-half to 10 lbs. of the dry hydroxide per 1000 gallons of oil affords some degree of correction when added to the neutral oil at the end of the steaming period, but this method of treating corrosive oils has several notable objections, the chief among these being the severe degradation in color which takes place and tendency for the finished white oil from the clay percolating filters to become cloudy after a comparatively short period of time.

It has now been found that acid-treated oils which fail to pass the copper strip test after finishing by percolation thru clay, because of their corrosive characteristics, may be treated in the neutral condition in such a manner that all corrosiveness is prevented and their color is much improved.

The present invention is an extension of the process of treating neutral white oils or other acid-refined oils, such as mineral oils or lubricating oils, with alcoholic potassium hydroxide but is devoid of the objectionable features which are in hand in the process of treating these oils when only alcoholic potassium hydroxide is used.

The present invention comprises a process of treating an oil with a solution of an alkali metal hydroxide or alcoholate, for example, alcoholic potassium hydroxide or alcoholic sodium or potassium alcoholate in combination with a hydro or thermally decomposable metallo-organic compound, the metallic constituents of which, upon decomposition, are characterized by forming amphoteric oxides or hydrated oxides, and the organic constituents liberated by the decomposition of the metallo-organic compound are characterized by being volatile under the conditions of temperature at which the oil is treated. Samples of metals which form amphoteric hydrated oxides are aluminum, tin, zinc, etc., and the preferred metallo-organic compounds formable from these metals are the metal alcoholates, although other negative radicals may be used to form compounds such as metallic alkyl derivatives or metallic alkyl halogen derivatives may be used.

More particularly, the invention contemplates taking a corrosive oil in its neutral state after steaming out the solvent used to remove the alkali sulfonate and heating the oil to from 90-150° C., preferably 125° C., and adding to the hot

oil the alkali compound in an amount equivalent to from $\frac{1}{2}$ to 10 lbs. of dry alkali hydroxide per 1000 gallons of oil, blowing with either hot air freed of carbon oxides, a mixture of hot air and water vapor freed of carbon oxides, or steam, for a time sufficient to secure intimate contact between the oil and the alkali compound, this is usually from 15 to 30 minutes. The metallo-organic compounds are then added in an amount such that decomposition yields hydrated oxides in the range between .5 and 15 lbs. per 1000 gallons of oil. The oil is then again blown with a finely dispersed stream of hot moist air free of carbon oxides for from 15 to 30 minutes, or for a length of time sufficient to decompose the metallo-organic compounds. For most purposes the passage of air thru the mixture furnishes sufficient agitation to insure an intimate contact between the oil and the reagent. However, additional agitation may be secured by mechanical means, such as propeller mixers, centrifugal mixers, such as turbo-mixers or recirculation thru a pump and the like. The process may be run continuously by concurrent addition of the reagents to the oil in a packed or bubble plate column while countercurrently blowing with moist air or steam. The organic decomposition products of the metallo-organic compounds having been removed during the second air-blowing step in the process, it is advantageous at this point to remove the precipitated oxide in its hydrated form and this can be done by allowing the oil to settle, by centrifuging or by filter-pressing. The filter may be of the blotter, plate and frame or rotary type, and a commercial siliceous filter aid may be used either as a precoat on the filter or mixed with the oil before filtering. After the removal of the hydrated oxides, the oil is found to be much improved in color and for some grades of oils no further treatment designed to improve color is necessary. For highly refined oils, such as medicinal oils which must be colorless, tasteless and odorless, further treatment with a sorptive material, such as fuller's earth, bauxite, Attapulgus clay or activated charcoal, may be required. This further improvement of color is accomplished by contacting the oil with the sorptive material in a powdered form or by percolation thru a bed of granular sorptive material of from 30 to 40 mesh.

The following example is given for the purpose of illustrating the invention:

Example 1

1000 gallons of an acid-treated neutral white oil which had a Saybolt color of -4 and a Universal Saybolt viscosity of 85 seconds at 100° F. was treated at 125° C. with an isopropyl alcohol solution of potassium hydroxide containing 6 lbs. of KOH and blown for 15 min. with a finely dispersed stream of air which had been soda-washed to remove carbon dioxide and then saturated with water at 50° C. At the end of this period 33 lbs. of aluminum isopropylate dissolved in absolutely anhydrous isopropyl alcohol was added and air-blown with hot moist air for a further 30 min., maintaining the temperature at 125° C. The aluminum isopropylate decomposed to give isopropyl alcohol which was removed with the air and a finely dispersed precipitate of hydrated aluminum oxide. At the end of this period, when all of the alcohol was blown off, the oil was mixed with a small quantity of a diatomaceous filter aid and filtered on a filter press. Upon cooling, the oil had a +13 Saybolt color and gave

a pass 1 copper strip test after 2 hours whereas the original oil gave a does not pass 5 test under the same conditions. On percolating the treated oil thru 8% of an adsorbent clay, a water-white oil was obtained of a +30 up color which gave a pass 2 copper test after 2 hours whereas the original untreated oil failed to pass the copper strip test when percolated under the same conditions.

10 In companion experiments, different samples of the same oil were treated separately; one with KOH and the other with aluminum isopropylate in the same relative proportions as when used in combination so as to give blanks for comparison, 15 unsatisfactory results were obtained. These results are summarized in the table below.

TABLE 1
Treatment of neutral oil with alcoholic potassium hydroxide and aluminum isopropylate

	Sample			
	A	B	C	D
25 Temperature of treat ° C.	125	125	125	125
Time of air blowing minutes	30	15	30	45
Mgm. of KOH per 100 cc.	None	72	None	72
30 Mgm. of $\text{Al}(\text{OC}_3\text{H}_7)_3$ per 100 cc.	None	None	400	400
Equiv. mgm. of $\text{Al}(\text{OH})_3$ per 100 cc.	None	None	157	157
Saybolt color before percolation	-4	-13	+10	+13
35 2 hour copper before percolation	DNP 5	DNP 3	DNP 5	Pass 1
3 hour copper before percolation	DNP 5	DNP 3	DNP 5	Pass 2
Saybolt color after percolation	+30 up	+27	+30 up	+30 up
2 hour copper after percolation	DNP 5	Pass 2	DNP 5	Pass 2
40 3 hour copper after percolation	DNP 5	DNP 3	DNP 5	Pass 2

Sample A is the original untreated oil blank.

Sample B is the original oil treated with only potassium hydroxide.

Sample C is the original oil treated with only aluminum isopropylate.

45 Sample D is the original oil treated with both potassium hydroxide and aluminum isopropylate.

It is supposed that the KOH enters into combination with some material, probably related to a sulfonic acid, which has a chromophoric nucleus, but of sufficiently high enough molecular weight to still remain oil-soluble. When the oil is then treated with a soluble metallo-organic compound which decomposes in situ to give an insoluble, highly adsorbent amphoteric oxide or hydrated oxide, the KOH is adsorbed on the surface of the hydroxide, taking with it the corrosive constituents present and any colored material which it is associated with. It is for this reason that the combination of reagents results in better color improvement than when any of the color reagents are used singly, in spite of the fact that when the KOH is used alone, considerable increase in color results.

The foregoing disclosure and examples are given for the purposes of illustration only and are not to be construed as in any way limiting the invention.

What is claimed is:

1. The process of improving the color and reducing the corrosiveness of acid-treated oils on copper which comprises treating the oil in its neutral state first with strong alkali, then with a compound having the formula $\text{Me}(\text{X})_n$, where Me is a metal selected from the group consisting of aluminum, tin and zinc; X is a radical selected

from the group consisting of alkyl, alkoxy, and alkylhalide radicals, n is a number equal to the valence of the metal radical selected and freeing the oils from the products of reaction.

2. The process of improving the color and reducing the corrosiveness of acid-treated oils on copper which comprises treating the oil in its neutral state first with potassium hydroxide then with a compound having the formula $Me(X)_n$, where Me is a metal selected from the group consisting of aluminum, tin and zinc; X is a radical selected from the group consisting of alkyl, alkoxy, and alkylhalide radicals, n is a number equal to the valence of the metal radical selected and freeing the oils from the products of reaction.

3. The process of improving the color and reducing the corrosiveness of acid-treated oils on copper which comprises treating the oil in its neutral state with alcoholic potassium hydroxide, blowing with air freed of carbon oxides, adding a compound having the formula $Me(X)_n$, where Me is a metal selected from the group consisting of aluminum, tin, and zinc; X is a radical selected from the group consisting of alkyl, alkoxy, and alkylhalide radicals, and n is a number equal to the valence of the metal radical selected, blowing the oil with warm moist air freed of carbon oxides and freeing the oil from the products of reaction.

4. The process of improving the color and reducing the corrosiveness of acid-treated oils on copper which comprises treating the oil in its neutral state with potassium alcoholate, blowing with air freed of carbon oxides, adding a compound having the formula $Me(X)_n$, where Me is a metal selected from the group consisting of aluminum, tin, and zinc; X is a radical selected from the group consisting of alkyl, alkoxy, and alkylhalide radicals, and n is a number equal to the valence of the metal radical selected, blowing with warm moist air freed of carbon oxides and freeing the oil from the products of reaction.

5. The process of improving the color and reducing the corrosiveness of acid-treated oils on copper which comprises treating the oil in its neutral state first with strong alkali, then with an organic compound of aluminum, the organic radical of which is selected from the group consisting of alkyl, alkoxy and alkylhalide radicals, blowing with warm moist air freed of carbon oxides and freeing the oil from the products of reaction.

6. The process of improving the color and reducing the corrosiveness of acid-treated oils on copper which comprises treating the oil in its neutral state first with strong alkali, then with aluminum alcoholate, blowing with warm moist air freed of carbon oxides and freeing the oil from the products of reaction.

7. The process of improving the color and reducing the corrosiveness of acid-treated oils on copper which comprises treating the oil in its neutral state first with strong alkali, then with tin alcoholate, blowing with warm moist air freed of carbon oxides and freeing the oil from the products of reaction.

8. The process of improving the color and reducing the corrosiveness of acid-treated oils on copper which comprises treating the oil in its neutral state first with strong alkali, then with zinc alcoholate, blowing with warm moist air freed of carbon oxides and freeing the oil from the products of reaction.

9. The process of improving the color and reducing the corrosiveness of acid-treated white oils which comprises heating the oil to from 90-150° C., adding alcoholic potassium hydroxide in an amount equivalent to from .5 to 10 lbs. of KOH per 1,000 gallons of oil, blowing with air freed of carbon oxides, adding a compound having the formula $Me(X)_n$, where Me is a metal selected from the group consisting of aluminum, tin, and zinc; X is a radical selected from the group consisting of alkyl, alkoxy, and alkylhalide radicals and n is a number equal to the valence of the metal radical selected in an amount equivalent to

30 35 1.5-15 lbs. of amphoteric hydrated oxide per 1000 gallons of oil, blowing with hot moist air freed of carbon oxide and filtering and percolating the filtered oil through a sorptive material.

10. The process of improving the color and reducing the corrosiveness of mineral white oil on copper which comprises heating the oil to 125° C., adding alcoholic potassium hydroxide in an amount equivalent to between .5-10 lbs. of potassium hydroxide per 1000 gallons of oil, thoroughly agitating the mixture, adding aluminum isopropylate in an amount equivalent to between 1.5-15 lbs. of hydrated aluminum oxide per 1000 gallons of oil, blowing with warm moist air until all of the aluminum alcoholate has been decomposed, filtering and percolating the oil through a bed of sorptive material.

CHARLES A. COHEN.
